UNITED STATES PATENT OFFICE.

JOHN DOUGLAS, OF ELIZABETH, NEW JERSEY, ASSIGNOR TO THE SINGER
MANUFACTURING COMPANY OF NEW JERSEY.

PLAITING ATTACHMENT FOR SEWING-MACHINES.

SPECIFICATION forming part of Letters Patent No. 488,547, dated December 27, 1892.

Application filed October 7, 1892. Serial No. 448,135. (No model.)

To all whom it may concern:

Be it known that I, JOHN DOUGLAS, a citizen of the United States, residing at Elizabeth, in the county of Union and State of New Jersey, have invented certain new and useful Improvements in Plaiting Attachments for Sewing-Machines, of which the following is a specification, reference being had therein to the accompanying drawings.

10 My invention relates to that class of devices which are adapted to form tucks or plaits in cloth and to guide the same to the stitch forming mechanisms of sewing machines so that said tucks or plaits may be 15 properly stitched; and my invention has for its object to provide a plaiting device by means of which two tucks or plaits, which are formed so as to lie in the same direction, may be simultaneously made and guided to 20 the stitch-forming mechanism of a two-needle sewing machine, as well as to provide means whereby the presser-foot of the machine may be lifted and the plaiting blades be, at the same operation, moved aside for the insertion 25 or removal of the work.

In the accompanying drawings, Figure 1 is a side view of a sewing machine with my invention applied thereto, and Fig. 2 is a front end view of the same. Fig. 3 is a detail view 30 showing part of the connections between the presser lifter plaiting-blade carrying lever.

A denotes the arm and B the work-plate of a sewing machine which, in its general construction, may be of any well-known type.

35 To the rear side of the horizontal part of the arm B is pivoted a presser-foot lifting lever C, the forward end of which hooks beneath the upper end of an arm or bracket d attached to the presser bar D, to the lower 40 end of which latter is secured the presser foot d'.

To the rear end of the lever C is attached a rod c which extends down through the work-plate of the machine and which is to be connected with any suitable foot or knee-operated device (which may be of any of the forms now in use) so that, without the use of the hands, the operator may lift the presser-foot. 45

E is the needle-bar, herein shown as carry-

ing two needles e for forming two rows of 50 stitches, any well-known forms of shuttles or loopers co-operating with these needles.

Attached to the work-plate B is a guide to co-operate with the plaiting blades and consisting, as herein shown, of two guiding portions or blocks b and b', the inner or guiding faces of which are in different vertical planes and are both faced in the same direction, and two blades b² and b³, and also both facing or extending in the same direction and the latter of which extends inward beyond and thus overlaps the former, so that their inner or working edges are also in different vertical planes.

Pivoted to the forward depending part of 65 the arm A is a lever F, herein shown as being provided with two plaiting blades f and f', both facing or extending in the same direction, the former being above and extending outward beyond or over-lapping the latter, 70 these plaiting blades intermeshing with the blades b² and b³ of the stationary guide, are shown clearly in Fig. 1, when the parts are in their operative positions, their outer or working edges being in different vertical planes. 75 The lever F is provided with a stop-screw f² which impinges against an abutment or bracket a secured to the forward part of the arm A, said stop being normally held in contact with said abutment by the spring a' 80 which, as herein shown, is connected to a second lever F' intermeshing at its upper end with the lever F, as in the plaiting device covered by United States Patent No. 480,260; said lever F' being also provided with a stop-screw 85 f³. If, instead of forming two plaits folded in the same direction, it be desired to simultaneously form two plaits folded in opposite directions the levers F and F' will carry two oppositely arranged plaiting blades, as shown 90 in the said patent; and it will be obvious that the mechanism presently to be described for moving the plaiting blades aside when the work is to be inserted, may be used in connection with the arrangement of plaiting 95 blades shown in said patent as well as with the arrangement of plaiting blades herein shown.

Journaled in the bracket A' attached to the lower depending part of the arm A is a rock-shaft H the rear arm h of which is connected by the link g with the forward end of the lever C, said rock-shaft having a second arm h' connected by a link i with the lever F. The link i is provided with a slot i' in which the screw or pin i² carried by the arm h' has free play, so as to afford a loose connection between said arm h' and the link i which will permit the rock-shaft H, which is connected with the lever C, to be moved slightly without moving the plaiting blades. In other words the slot and pin connection above-described affords such a loose connection between the presser foot lifting device and the lever or levers which carry the plaiting blades connected to the said lifting device that the presser foot may be raised from the work by a partial operation of the lever C, without disturbing the plaiting blades; but by a full operation of the presser-foot lifting lever C the presser-foot will first be lifted and the plaiting blades will then be swung aside for the insertion or removal of the work.

In the operation of my invention the operator, when the work is to be inserted, depresses the rod c, thereby lifting the presser-foot and swinging aside the plaiting blades so that the latter will be clear of the stationary guide fixed to the work-plate. The fabric to be plaited is now laid on the stationary guide and the rod c being released the spring a' and the presser-bar depressing spring will return the parts to their normal positions shown in Figs. 1 and 2 of the drawings, and the machine being started the plaits formed by the plaiting blades and the co-operating guide will be directed to the needles to be stitched down, as will be readily understood.

More than two plaiting blades carried by the lever F, with corresponding parts on the stationary co-operating guide, may be employed, if it be desired to form more than two plaits at once, this part of my invention comprising a plurality of plaiting blades movable with relation to a corresponding number of co-operating parts of a stationary guide.

Having thus described my invention I claim and desire to secure by Letters Patent:

1. In a plaiting attachment for sewing machine, the combination with a movable arm or lever carrying a plurality of plaiting blades having their working edges in different vertical planes and facing in the same direction, of a fixed guide having a plurality of guiding faces in different vertical planes, and a plurality of guiding blades also having their working edges in different vertical planes, said faces and blades all facing in the same direction.

2. The combination with a sewing machine provided with a plurality of stitch-forming devices, of a guide having a plurality of guiding faces in different vertical planes and having also a plurality of guiding blades, said

guiding faces and blades all facing in one direction, and the working edges of which are also in different vertical planes, and a plurality of plaiting blades facing in one direction and arranged to intermesh with said guiding blades, said plaiting blades also having their working edges in different vertical planes.

3. The combination with the fixed guide consisting of the guiding parts of blocks b and b' having their inner or working edges in different vertical planes and the guiding blades b² and b³ also having their guiding edges in different vertical planes, said edges and blades all facing in the same direction, of the pivoted lever F carrying the plaiting blades f and f' both facing in one direction and normally intermeshing with the said guiding blades and also having their outer or working edges in different vertical planes.

4. In a sewing machine, the combination with a presser-bar and presser foot and a lifting device therefor, of a plaiting attachment comprising swinging plaiting blades connected with the said lifting devices so that they may be swung aside from operative position relative to said presser foot when the latter is raised by said lifting device.

5. In a sewing machine, the combination with a presser-bar and a lifting device therefor, of a plaiting attachment comprising movable plaiting blades having a loose connection with the said lifting device, whereby, in the operation of the lifting device, the presser foot may be raised without moving the plaiting blades, or the presser foot be raised and the plaiting blades be subsequently removed from operative position by one and the same operation of the lifting device.

6. In a sewing machine, the combination with a presser bar and a lifter therefor having connections by which it may be operated from beneath the work-plate, of a plaiting attachment comprising movable plaiting blades connected with the said lifter so that they may be removed from operative position thereby.

7. The combination with the presser bar D provided with the arm or bracket d and the presser foot d', of the lifting lever C the forward end of which engages the said arm or bracket and the rear end of which is provided with a rod c' extending down beneath the work-plate of the machine, the plaiting-blade carrying-lever F, the rock-shaft H having arms h and h', the link g connecting said arm h with the lever C, and the link i connecting the said arm h' with the said lever F.

8. The combination with the presser bar D provided with the arm or bracket d and the presser foot d', of the lifting lever C the forward end of which engages the said arm or bracket and the rear end of which is provided with a rod c' extending down beneath the work-plate of the machine, the plaiting-blade carrying-lever F, the rock-shaft H having

arms *h* and *h'*, the link *g* connecting said arm *h* with the lever *C* and the link *i* connecting the said arm *h'* with the said lever *F*, said link *i* being provided with the slot *i'* entered by a screw or pin *i²* carried by the said arm *h'* to form a loose connection between the said lifting lever and the said lever *F*.

In testimony whereof I affix my signature in presence of two witnesses.

JOHN DOUGLAS.
